US0D1025912S

(12) **United States Design Patent** (10) **Patent No.:** **US D1,025,912 S**
(45) **Date of Patent:** **** May 7, 2024**

(54) **POWER SUPPLY UNIT**

(71) Applicant: **NINGBO GONEO DIGITAL TECHNOLOGY CO., LTD.**, Ningbo (CN)
(72) Inventors: **Jianeng Chang**, Zhejiang (CN); **Yun Gao**, Zhejiang (CN)

(**) Term: **15 Years**

(21) Appl. No.: **35/517,596**

(22) Filed: **Apr. 19, 2023**

(80) **Hague Agreement Data**

Int. Filing Date: **Apr. 19, 2023**

Int. Reg. No.: **DM/229634**

Int. Reg. Date: **Apr. 19, 2023**

Int. Reg. Pub. Date: **Jun. 23, 2023**

(30) **Foreign Application Priority Data**

Nov. 4, 2022 (CN) 202230735624.3
